UNITED STATES PATENT OFFICE.

GAETANO GERACE, OF WINDSOR, ONTARIO, CANADA.

WILLOW-BARK-STRIPPING MACHINE.

1,399,957.

Specification of Letters Patent. Patented Dec. 13, 1921.

Application filed August 17, 1921. Serial No. 493,137.

To all whom it may concern:

Be it known that I, GAETANO GERACE, a subject of the King of Italy, residing at Windsor, in the county of Essex and 5 Province of Ontario, Canada, have invented certain new and useful Improvements in a Willow-Bark-Stripping Machine, of which the following is a specification.

My invention relates to improvements in 10 bark strippers, and more particularly to machines for the purpose of stripping the bark from willow stems to be used in the manufacture of wicker ware and the like, and consists essentially of a roller press, a 15 pair of opposed scrapers tensioned together and yieldable to the willow passing between, and an endless belt carrying a plurality of yieldable blades operating transversely of the machine, said blades being rigid with 20 the belt and projected at right angles thereto and extending to a point just beyond the contact of said opposed scrapers.

The invention has for its object to provide a machine for effectively and efficiently 25 removing the bark from willow, and at the same time to provide such a machine which will be simple, durable, and inexpensive to manufacture.

These, together with further objects, may 30 be attained by the construction, combination and arrangement of the parts as will be hereinafter more fully described, illustrated in the accompanying drawing, and pointed out in the claim hereunto appended.

Reference may now be had to the accompanying drawing, in which:

Figure 1 is a left side elevation of the entire machine;

Fig. 2 is a right side view of the central 40 portion of the machine;

Fig. 3 is a front elevation of Fig. 2 showing the framework in section; and

Fig. 4 is a sectional elevation taken on the line X-X in Fig. 1.

Similar reference characters refer to similar parts throughout the several views.

The framework of the machine comprises a plurality of uprights A connected at the top by transverse cross members B, and in 50 terposed dividing blocks D.

The said uprights are vertically slotted as indicated by 2, to accommodate the vertically operative presses comprised of an upper transverse cross head 3 provided with 55 a leaf spring 4 bearing against a lower cross head carrying journal boxes 5 in which is

journaled the shaft 6 carrying the rubber roller 7 for example. The outer end parts of said shaft have rigid thereon pinions 8 meshed with and driven by pinions 9 mounted on the shaft 10 having bearing in the rigid journal box 11 and provided with a similar rubber roller 12 engaging the surface of the formerly mentioned roller.

The shafts 10 extend to the left of the 65 machine beyond the pinions 9 and are provided with sprockets 13. A sprocket chain 14 passes around the two end sprockets 13 of the machine, engaging the intermediate sprockets, as illustrated in Fig. 1, and is 70 driven by the pulley 15 rigid on the shaft carrying the forward sprocket, which is driven by the belt for example. It will be noted therefore that the rollers in each upright are rotated simultaneously. The tension of the upper and lower rollers is governed and adjusted by hand press screws 17 threaded in the cross members B.

18 are shelves, supported by brackets 19, leading to and from the rollers 7, 12.

20 and 21 are top and bottom scrapers respectively having surface contact with each other, the contacting edges thereof being serrated or notched as indicated by 22, the notches being staggered in relation as illustrated, constituting flat staggered scraping teeth. The upper or top scraper 20 is dovetailed into a holder 23, and both scrapers are provided with perpendicular registered holes through which pass the retaining rods 90 24 which are removably secured to a block D by their hooked ends 25.

The holes in the lower scraper are somewhat larger than those in the upper for a purpose which will hereinafter be apparent. 95 The upper scraper is tensioned against the lower by means of the spiral push springs 26 which are inserted between the two center cross members B.

The lower scraper 21 is pivotally connected at one end thereof to the adjacent upright A, as indicated at 27, and is connected at its opposite end to a foot pedal 28 by means of a connecting link 29. The said foot pedal is pivoted to the adjacent upright 100 at 30 and is upwardly tensioned by the spiral push spring 31. It will here be seen that the lower scraper is normally tensioned against the upper scraper, but may be disengaged by pressure upon the pedal 28.

An endless belt 31 is carried by pulleys 32 rigid on shafts 33, 34, running longitudi-

nally of the machine, on the left and right sides thereof respectively, journaled in bearings 35, 36, respectively. The said belt is provided with a plurality of resiliently yieldable metallic strippers 37 which project normally at right angles therefrom and which when traveling uppermost of said pulleys their upper ends project slightly above the horizontal plane of the toothed 10 portions of the scrapers 20, 21. The pulley 32 on the right of the machine mounted on the shaft 34 is the drive pulley and is driven by the worm gear 38 in mesh with the worm 39 mounted on the adjacent shaft 10.

15 The operation of the device is as follows: The willow stems are inserted into the machine along the line of the forward or front shelf 18, between the rollers 7, 12, as indicated by the heavy arrows in Figs. 1 and 2.

20 The operator depresses the lower scraper 21 by foot action upon the pedal 28 in order to admit the ends of the stems between the two scrapers. The bark is substantially stripped from the stems by the action of the 25 scrapers aforesaid while the stems are forcibly passed therebetween by the section of the plurality of rollers.

Subsequently to the stems passing between the scrapers, the strippers 37 relieve them of 30 any remaining bark that has escaped the action of the scrapers. The stripped bark is then carried between the remaining rollers, after which it is expelled from the machine in a completely stripped condition.

35 Having now fully described my invention,

what I claim and desire to secure by Letters Patent is:

In a machine of the class described, the combination with a suitable frame, a horizontally arranged plurality of paired conveying rollers journaled in the frame, means for actuating said rollers simultaneously in a common direction, an upper transversely mounted scraper having a notched lower edge and tensioned downwardly, a lower scraper mounted parallel with the upper scraper and in a common vertical plane and having a notched upper edge tensionally engaging the notched edge of the upper scraper, means for separating said scrapers when required, a horizontal belt running transversely of the frame and mounted on pulleys journaled therein, a plurality of tensionally yieldable metallic strippers secured to said belt at spaced intervals and extending normally at right angles therefrom, those of said plurality of strippers traveling upwardly of said pulleys extending slightly above the horizontal plane of the notched edges of said scrapers, means for actuating said belt simultaneously with said rollers, and means for tensioning each pair of said rollers.

In testimony whereof I have affixed my signature.

GAETANO GERACE.
